UNITED STATES PATENT OFFICE.

EDWARD C. MEIER, OF PHOENIXVILLE, PENNSYLVANIA.

BOILER CONSTRUCTION.

1,271,598.

Specification of Letters Patent. Patented July 9, 1918.

Application filed April 10, 1917. Serial No. 181,090.

To all whom it may concern:

Be it known that I, EDWARD C. MEIER, a citizen of the United States, residing at Phoenixville, in the county of Chester and State of Pennsylvania, have invented certain new and useful Improvements in Boiler Constructions, of which the following is a specification.

My invention consists of an improved boiler construction, one object being to provide feed water conducting elements which are so constructed and arranged that they will greatly add to the efficiency of the boiler.

Another object is to provide baffling means which will cause an economical circulation for the hot products of combustion and will cause them to effectively heat the feed water elements and other portions of the boiler.

A further object is to so design my invention that it will be of comparatively simple construction.

These objects, and other advantageous ends which will be described hereinafter, I attain in the following manner, reference being had to the accompanying drawing in which—

The figure represents a sectional elevation of an upright water tube boiler which is constructed in accordance with my invention.

Referring to the drawing, 1 represents the boiler casing having an outlet passage 2 formed in the rear thereof to permit the products of combustion to pass outwardly to a flue (not illustrated).

A pedestal 3 is located within the casing and between this pedestal and the front wall 5, is located a wall 4. A grate 6, which may be of any suitable construction, has a stepped upper surface 7 which forms the fuel supporting surface and extends from the front wall 5 to the wall 4.

Two boiler units 8 and 9 are arranged within the casing 1, the boiler unit 8 comprising a plurality of water tubes 10 connecting at their top and bottom with drums 11 and 12. The boiler unit 9 includes a plurality of tubes 13 which connect at their top and bottom with drums 14 and 15.

The drums 11 and 14 are connected by tubes 16, and the drums 12 and 13 are connected by tubes 17, it being noted that the tops of the drums 11 and 14 are also connected by a tube 18 which acts as an equalizing tube between the steam spaces of the drums 11 and 14.

The drum 14 has a main steam pipe 19 leading therefrom. The drums 11, 12, 14, and 15, are arranged horizontally and supported within the side walls, the drum 12 being further supported by the pedestal 3. The drum 15 is also supported by a pedestal 20 which is mounted, together with the pedestal 3, on the floor of the casing.

The drums 11 and 12 are in different vertical planes so that the tubes 10 extend at an incline toward the front wall 5 of the casing. This is also true of the drums 14 and 15 so that the tubes 13 also extend at an incline and substantially parallel with the tubes 10 of the boiler unit 8.

A baffle 22 is provided between the tubes 10 and extends upwardly from the drum 12 throughout a portion of the length of said latter tubes, stopping short of the drum 11 so as to provide a passage 21 between it and the drum 11.

Another baffle 23 is arranged between the tubes 13 of the boiler unit 9 and extends downwardly from the drum 14 and stops short of the drum 15 to provide a passage 24 between the lower end of the baffle 23 and the drum 15.

A fifth drum 25 is mounted in the upper rear portion of the casing 1 and this drum has a feed water inlet pipe 26 connected therewith. A plurality of rows of feed water tubes 27 extend downwardly from the drum 25 and connect with the drum 15. These tubes 27 are located between the rear tubes 13 of the boiler unit 9 and the rear wall 28 of the casing 1. A baffle 29 is located against the forward portions of the front row of tubes 27 and extends upwardly from the drum 15 toward the drum 25 and stops short of said latter mentioned drum to provide a passageway 30. The baffle 29 thus confines the tubes 27, throughout the greater portion of their lengths, between it and the rear wall 28 so that the products of combustion, as will be hereinafter more fully described, are compelled to pass along the tubes 27 prior to their passing out of the outlet passage 2.

In operation, the products of combustion pass upwardly from the fire box 31 into contact with the tubes 10 of the boiler unit 8, which are forward of the baffle 22. They then pass through the passage 21 provided between the top of the baffle 22 and the drum 11. After passing through the passage 21, said products pass downwardly be-

tween the baffles 22 and 23 to heat the rear tubes of the boiler unit 8 and the forward tubes of the boiler unit 9. These products are prevented from passing downwardly between the drums 12 and 15 by a baffle arch 32 which rests on the upper tubes 17 and extends between the drums 12 and 15.

These products are thus compelled to pass through the passage 24 and upwardly between the rear face of the baffle 23 and the forward face of the baffle 29 in order to heat the rear tubes 13 and to engage the drum 25 and the upper portions of the tubes 27. All of the products of combustion then pass through the passageway 30 and downwardly between the baffle 29 and the rear wall 28, and thus heat the tubes 27 throughout their entire length prior to passing out of the outlet passage 2.

20 It will thus be noted that by having a plurality of tubes which communicate with the drums 25 and 15 and arranging these tubes and the drum 25 in the positions above described, the water contained therein will be heated to a high temperature prior to entering the boiler units proper. This adds greatly to the efficiency of the boiler and to its capacity as a steam generator. In the accompanying drawing I have illustrated 30 three rows of tubes 27, however, it will be understood that a greater number of rows may be used if desired.

While I have illustrated a boiler including two boiler units, it will be understood that 35 any number of units may be inserted within the casing without departing from the spirit of my invention.

While I have described my invention as taking a particular form, it will be understood that the various parts of my invention 40 may be changed without departing from the spirit thereof, and hence I do not limit myself to the precise construction set forth, but consider that I am at liberty to make such 45 changes and alterations as fairly come within the scope of the appended claims.

Having thus described my invention, what I claim as new and desire to secure by Letters Patent is:

50 1. The combination in a boiler of a casing; a boiler unit within said casing; an independent feed water drum within the top of said casing; means for conducting feed water to the drum, said boiler unit having an upper and a lower drum connected by tubes, said lower drum being mounted below said independent feed water drum; a plurality of tubes connecting the lower drum of the boiler unit with said feed water drum; a 55 baffle leading downwardly from the upper

drum of the boiler unit and supported by the tubes thereof, said baffle stopping short of the lower drum to provide a passage for the products of combustion; and a second baffle extending from said lower drum toward said feed water drum and located to the rear of said first baffle and passage and in front of the tubes connecting with the feed water drum, said second mentioned baffle stopping short of the feed water drum to provide a 70 passage for the products of combustion between said latter tubes and between said second mentioned baffle and the rear of the casing, said casing having an outlet passage for the products of combustion below and to 75 the rear of said second mentioned passage, substantially as described.

2. The combination in a boiler of a casing; a boiler unit within said casing; an independent feed water drum within the top of said casing; means for conducting feed water to the drum, said boiler unit having an upper and a lower drum connected by tubes, said lower drum being mounted below said independent feed water drum; a plurality of tubes connecting the lower drum of the boiler unit with said feed water drum; a baffle leading downwardly from the upper drum of the boiler unit and supported by the tubes thereof, said baffle stopping short of the lower drum to provide a passage for the products of combustion; a second baffle extending from said lower drum toward said feed water drum and located to the rear of said first baffle and passage and in front of the tubes connecting with the feed water drum, said second mentioned baffle stopping short of the feed water drum to provide a 80 passage for the products of combustion between said latter tubes and between said second mentioned baffle and the rear of the casing, said casing having an outlet passage for the products of combustion below and to 85 the rear of said second mentioned passage; a second boiler unit within said casing and located to the front of said first boiler unit, said second boiler unit including an upper and lower drum connected by tubes; and a baffle extending upwardly from said latter lower drum and stopping short of the upper drum of said second unit, substantially as 90 described.

In testimony whereof I have signed my name to this specification in the presence of two subscribing witnesses.

EDWARD C. MEIER.
